AUTOMATIC ADJUSTABLE WAISTBAND

Ralph R. Fanning, Celina, Ohio, assignor to
Winner, Inc., Berne, Ind., a corporation of
Indiana

Original application November 24, 1947, Serial
No. 787,053, now Patent No. 2,526,813, dated
October 24, 1950. Divided and this application
September 1, 1950, Serial No. 186,693

1 Claim. (Cl. 2—237)

1

This invention relates to improvements in garments, and more particularly to a waistband for trousers and like garments that are automatically adjustable in size to the waist of the wearer. The case is a division of my copending application, now Patent 2,526,813, October 24, 1950.

The object of the invention is to provide an automatically adjustable waistband for garments, of simple and economical construction, which is automatically adjusted to the waist of the wearer.

Another object of the invention is to provide an automatically adjustable waistband for garments which conceals the point of adjustment within a plait formed in the side of the garment.

A further object of the invention is to provide an automatically adjustable waistband for trousers which conceals the point of adjustment within side pockets in such a way as to afford side pockets of normal proportions and construction, thus avoiding unsightly wrinkles and gatherings.

Another object of the invention is to provide a waistband that adjusts itself without the use of buckles, clasps and the like, to the waist of the wearer.

A further object of the invention is to provide an automatically adjustable waistband that may be attached to existing styles of trousers.

A further object of the invention is to provide an automatic adjustable waistband for trousers that permits the elimination of the use of a belt and suspenders as well as belt loops and tunnel loops.

A further object of the invention is to provide an automatically adjustable waistband that always presents a neat and close fit about the waist.

Another object of the invention is to provide an adjustable waistband that is automatically extensible and contractible within the locus of the waistband to fit the waist of the wearer.

A further object of the invention is to provide an adjustable waistband that is automatically extensible and contractible within a wide range of adjustments to fit the waist of the wearer in all sitting, bending, lying and standing positions.

A still further object of the invention is to provide an automatically adjustable waistband having sufficiently wide forward elastic elements which will distribute the tension applied over the abdomen in such a way as to render proper abdominal support, thereby replacing separate abdominal support devices where their need is indicated.

In the accompanying drawing forming a part of this specification and in which like numerals are

2

employed to designate like parts throughout the same:

Figure 1 is an elevational view of the automatically adjustable waistband.

5 Figure 2 is a view similar to that of Figure 1, but showing the waistband and the side pocket in extended position.

Figure 3 is a view of the form shown in Figure 1 as viewed from the inside of the garment.

10 Figure 4 is a sectional view along the section 4—4 of Figure 3.

Figure 5 is a view of Figure 3 with the garment in extended position, and

15 Figure 6 is an elevational view showing an alternative way of attaching an end of an elastic to the waistband lining by means of forming a plait in the lining.

The double acting elastic assembly is shown 20 associated with a continuous front garment so as to automatically adjust the same around the waist of the wearer. In Figure 1, the front panel is indicated at 50, while the rear panel is indicated at 51. The rear panel extends forward to a seam 52 by which it is attached to a forward extending

25 flap or pocket facing 51a extending forward to where its forward edge 53 is attached to the adjacent inner wall of the side pocket by stitching 53', see Figures 1 to 5. The flap portion 51a, as will be seen in Figures 1 and 2, lies behind the outer wall of the side pocket to be described later. 30 The seam joining the rear panel 51 and the flap portion 51a extends upward to a point indicated at a in Figures 1 and 2 thereby leaving unattached the forward upper portion of the rear panel extending between points a and b.

A rearwardly extending waistband portion 54 35 has its forward end attached to the front panel 50 by a seam at 55 from which it extends rearwardly behind the rear panel, as shown at point

40 a to point b and by the broken away portion of the rear panel 51 in Figures 1 and 2. A front waistband lining in the form of a facing or curtain piece 56, Figures 3 and 5, has its upper edge secured to the upper edge of the front panel 50

45 on the inside thereof, while its forward edge is sewn to the adjacent fly piece of the front panel. The portion along the rear edge of the lining 56 overlies and is attached to the front end of a second lining 57 that constitutes a rearward extension thereof and which has its upper edge portion secured to the upper edge portion of the adjacent front panel and the rearwardly extending waistband portion 54. The waistband lining or facing pieces 56 and 57 and the waistband portion 54 forms what is termed the front waistband.

Where the lining 57 extends behind the back side of the waistband portion 54, the lower edge is also stitched to the said waistband portion and forms therewith a tubular casing indicated generally at 58 in Figures 1 and 2. The lower edge of the linings 56 and 57 may be stitched throughout their entire length to the front panel 50, thereby forming a front tubular waistband section throughout their entire length.

Within the rear end of the tubular casing 58, there is inserted the front end of a rear elastic element 59 which is secured therein by stitching 60.

In Figures 3, 4 and 5, a rear waistband lining generally indicated at 61 in the form of a curtain is secured as by stitching to the upper edges of the rear panel 51 and the flap portion 51a, while its lower edge is unsecured except in the vicinity of the side pocket. This rear waistband lining 61 is in the form of a curtain and, as shown in Figures 3 and 5, is made up of three sectional pieces 62, 63 and 64, which overlie each other at their respective adjacent end portions. This lining 61 can be fabricated as a single piece of material. The lower edge of the curtain 61 is doubled over on itself and secured by a stitching indicated at 65. The stitching 65 can pass through the rear hip panel 51, thereby the waistband 61 will form with the adjacent portion of the rear panel 51 a rear tubular waistband.

Where the lining or curtain portions 62 and 63 overlie each other there is inserted therebetween the rear end of the rear elastic element 59 and the stitching indicated at 66 secures together those overlying parts and the end of the elastic element. In Figure 4, the section of curtain 63 is shown attached at its upper edge to the rear hip portion 51. The rear elastic element 59 is shown lying between the curtain 63 and the rear hip portion.

The curtain section 64 forms with the flap portion 51a, over which it lies, a tubular casing generally indicated at 67 in Figures 3 and 5. Within this tubular element is inserted a forward elastic element 68 which has its rear end secured between the overlying sections 63 and 64 of the waistband as by stitching 69 passing through the overlying sections and the elastic element. The forward end of the elastic element is secured between the overlying facing portions 56 and 57, above described, as by stitching 70, passing through the overlying facing and the elastic element. The forward elastic element 68 is free to move within the tubular casing generally indicated at 67.

In Figure 6, there is shown a modified way of attaching the elastic elements to their waistband portions. In this illustration, the attachment of the forward end of forward elastic element 67' is shown. The curtain or waistband is generally indicated at 61' and comprises a single strip as contrasted with the sectionally built-up curtain 61 shown in Figures 3 and 5. The curtain 61' has formed therein a plait 71 by merely folding a portion of the material of 61' back over itself. Within the plait 71, there is inserted the end of the elastic element 67' and stitching 72 passes through the plait and the elastic element. This same type of waistband construction can be utilized for attaching the rear ends of the elastic elements.

The side pocket 73 which is of normal proportions and construction comprises an outer wall 74 and an inner wall 75 which are jointed together at their forward edges to form an open loop or foldable portion as indicated at 76. In its most

forward position, the forward edge of the loop is indicated at 77 in Figures 1 and 3 while in its most rearward position, the forward edge of the plait is indicated at 77' in Figures 2 and 5. The rearward portion of the upper edge 78 of the outer wall 74, see Figure 5, is attached to the lower and adjacent edge of the front waistband lining 57 leaving the forward portion of the upper edge of the outer wall unsecured so as to form a portion of the open loop 76. The rear edge of the outer wall 74 is stitched to the rear edge or welt 55' of the front panel 50, see Figure 2. The inner wall 75 whose rear portion lies behind the flap portion 51a has the rearward portion of its upper edge 79, see Figures 3 and 5, stitched to the lower adjacent edge of the forward end of the rear waistband lining 61. The rear edge of the inner wall 75 is secured to the forward portion of the rear panel 51 by the seam at 52. The lower portions of the side walls 74 and 75 of the pocket are joined together at their rear and lower edges. This joint is below the pocket opening and the seam 52, see Figure 1, and allows the pocket 73 to swing free as a side swing pocket. The forward edge 53 of the flap portion 51a is secured, as described previously, to the adjacent portion of the inner pocket wall 75 by stitching 53'. Thus, the parallelly disposed elastic elements 59 and 68 provide double acting yieldable means that may be readily associated with a garment of the continuous front type at a minimum expenditure of time, labor and cost, so as to insure the garment securely and comfortably engaging the waist or hip portion of the wearer.

It can readily be seen that this form of waistband permits the elimination of the use of a belt and the customary belt loops and tunnel loops. It also conceals the elastic elements inside tubular and tubular like casings of the waistband which permits the elastic elements to be out of contact with the shirt or waist garment usually worn by the wearer. The elastic elements work against or in opposition to each other in holding the various parts of the form-fitting garment about the waist of the wearer so as to permit automatic adjustment to the waist of the wearer, and at the same time, affect a smooth, even appearance.

It will be understood that the invention is not limited to the illustrated details of construction but that variations in the form and arrangement of parts are contemplated under the claim which follows.

I claim:

A waistband garment of the class described comprising front and rear connected panels, said front and rear panels being disconnected at their upper portion to form a pocket opening, said front panel having a reduced rearwardly extending portion adjacent the waistline, a front waistband lining attached to the inner side of the front panel and said reduced portion and co-extensive in length therewith, said rear panel being formed with a forwardly extending flap underlapping the front panel adjacent to the pocket opening, a rear waistband lining secured to the inside of the rear panel and to said flap adjacent the waistline, said rear panel and said rear waistband lining forming an open ended belt receiving tube, a forward elastic element having one end connected to said front waistband lining and its opposite end received within the open ended tube and secured therein, said rear panel having a vertical slot at the waistline and adjacent the juncture of the flap therewith, said rearwardly extending reduced portion and said front waistband lining extend-

ing through said slot so that portions thereof are positioned between the rear panel and the rear waistband lining, a rear elastic element between the rear panel and the rear waistband lining, said rear elastic element being attached at one end to said rearwardly extending reduced portion of the front panel and said front waistband lining and its opposite end being secured to said rear waistband lining, a side pocket in said opening and having an inner wall and an outer wall, said outer wall being connected at its rear upper edge to said front waistband lining, the rear upper edge of said inner wall being connected to the lower edge of said rear waistband lining and to said flap, the forward upper edges of said side pocket being unattached and forming an open loop so that the walls of the pocket are movable with their respective waistband linings, and said elastic elements being disposed substantially parallel to each other and movable in opposite direc-

tions for automatically adjusting the waistband portion of the garment to fit the waist of the wearer.
